UNITED STATES PATENT OFFICE.

ROBERT T. JOHNSTON, OF TAUNTON, MASSACHUSETTS, ASSIGNOR TO THE CAMPBELL PRINTING PRESS & MANUFACTURING COMPANY, OF TAUNTON, MASSACHUSETTS.

MECHANICAL MOVEMENT.

No. 893,246.

Specification of Letters Patent.

Patented July 14, 1908.

Application filed July 27, 1905, Serial No. 271,472. Renewed November 21, 1907. Serial No. 403,189.

To all whom it may concern:

Be it known that I, ROBERT T. JOHNSTON, a citizen of the United States, residing at Taunton, in the county of Bristol and State of Massachusetts, have invented a new and useful Mechanical Movement, of which the following is a specification.

The object of this invention is to improve the well-known mechanical movement used 10 for reciprocating the beds of printing presses, which consists of a main driving mechanism and a reversing mechanism.

The particular object of the invention is to improve the main driving mechanism which 15 gives the bed its constant speed backward and forward movements. The main driving mechanism commonly employed for this purpose consists of two racks attached to the bed and a gear disposed between said racks 20 which gear is either moved up and down or slid axially to engage alternately with said racks.

When a rising and falling movement is imparted to the driving gear, a structure is 25 provided which is objectionable for the reason that the gear cannot be rigidly supported and which is apt to have lost motion; while when the gear is slid axially it must drive one rack at considerable distance from its support. I overcome these objections by setting the racks a distance apart a little greater than the diameter of the driving gear and in providing two intermediates which are slid laterally to engage the racks alternately.

30 The gear disposed between the racks is made wide-faced so that each intermediate is in mesh whether it is operating or not. The intermediates can be slid on rigid studs or bearings and as each intermediate only 40 comes into operation when it is in the plane of the racks, the parts will be rigidly supported when in operation.

The best form now known to me for practicing the invention is shown in the accompanying two sheets of drawings in which,

45 Figure 1 is a side elevation partly in section illustrating my invention, and Fig. 2 is a cross-sectional elevation thereof.

Referring to the drawings and in detail, A 50 designates the reciprocating bed or member which is mounted in the usual way so as to reciprocate on the frame of the machine.

B designates the impression cylinder and 55 10 designates a power shaft to which power may be applied from any suitable source by

means of pulleys 11—11. The power shaft carries a pinion 12 which meshes with a large gear 13 on the driving shaft 14. The gear 13 may also serve as an intermediate to drive the impression cylinder by meshing 60 with a large gear 15 secured thereon. The relation between the gears 13 and 15 is such that the driving shaft 14 makes three revolutions for each two revolutions of the impression cylinder; the mechanism being illustrated as applied to the ordinary two-revolution impression cylinder printing machine having a three-revolution driving shaft or movement.

Secured to the bed are upper and lower 70 racks 16 and 17. The inner end of the shaft 14 is journaled in a strong bracket 18. On the end of the shaft 14 is arranged a large wide-faced gear 19 which is disposed between the racks 16 and 17, the racks 16 and 75 17 being set so as to just clear said gear. A stud 20 is rigidly secured in said bracket 18. Loosely fitted on said stud 20 is an intermediate gear 21 which is hereinafter termed the upper intermediate. This gear is set to mesh 80 with the gear 19 and the upper surface of the same comes above the upper surface of the gear 19 in position to engage the upper rack 16. Also secured in the bracket 18 is a stud 22. Arranged on the same similarly to the 85 upper intermediate 21 is a lower intermediate 23 which is set in position to engage the lower rack 17. A lever 24 is pivoted on a stud 25 journaled in an arm projecting from the bracket 18. This lever has hooks 26 90 which engage the sides of the upper intermediate 21 and hooks 27—27 which engage the sides of the lower intermediate 23. By this arrangement, when one intermediate is moved into the plane of the racks 16 and 17, 95 the other intermediate will be moved out of position laterally to clear its rack.

28 designates a cam shaft. This cam shaft is driven by a pinion 29 secured on the driving shaft 14 which meshes with a gear 30 100 secured on the cam shaft 28; the reduction between the pinion 29 and the gear 30 being three to one so that the cam shaft 28 will make one revolution for each complete operation of the machine. Secured on the cam 105 shaft 28 is a cam 31. A lever 32 is mounted on a stud 33 and carries a roller 34 which engages the groove of the cam 31. The lever 32 is connected by a link 35 to the lower end of the rocking lever 24.

The gear 19 is made of the usual size; that is, if the improvement is applied to a three-revolution movement as shown, the circumference of said gear represents the length of 5 the constant speed forward and backward movements. A wrist-pin 36 may be set on said gear and may operate the usual yoke 37 from which the reversing movement is obtained, the details of which reversing movement are not described herein as they may be of any improved type and form no part of 10 the present invention.

In operation, the upper intermediate 21 engages the upper rack 16 for the return 15 movement of the bed and the lower intermediate 23 engages the lower rack 17 for the forward or printing movement of the bed. The intermediates are shifted during the reversing movement. This shift takes place 20 when no part of the work is being performed by the main driving mechanism and can be easily accomplished without wear. By this arrangement, the gear 19 is rigidly supported and each intermediate when it comes into 25 operation, is working close up to the bearing of its supporting stud. By this arrangement a strong, simple, accurately working main driving mechanism is provided.

The details and arrangements herein described may be greatly varied by a skilled 30 mechanic without departing from the scope of my invention as expressed in the claims.

Having thus fully described my invention, what I claim and desire to secure by Letters- 35 Patent of the United States is:—

1. In a mechanical movement, a main

driving mechanism comprising upper and lower racks, a gear arranged between the same of less diameter than the distance between the racks, two intermediates, and 40 means for bringing the intermediates alternately into operation.

2. In a mechanical movement, a main driving mechanism comprising upper and lower racks, a gear arranged between the 45 same of less diameter than the distance between the racks, two intermediates, and means for sliding the same axially to operate with said racks.

3. In a mechanical movement, a main 50 driving mechanism comprising upper and lower racks arranged in the same plane, a gear having a face wider than said racks and of less diameter than the distance between the racks, two intermediates continuously 55 meshing with said gear, and means for sliding the intermediates axially in opposition.

4. In a mechanical movement, a main driving mechanism comprising upper and lower racks, a wide-faced gear arranged between the same of less diameter than the distance between the racks, studs secured to the frame, intermediates journaled on said studs, and means for bringing the intermediates into operation alternately. 65

In testimony whereof I have hereunto set my hand, in the presence of two subscribing witnesses.

ROBERT T. JOHNSTON.
